PAGE 3

FIG. 6

FIG. 7

FIG. 8

FIG. 9

FIG. 10

In the drawing:

FIG. 1 is a top quarter perspective view of a flange, showing my new design;

FIG. 2 is a side elevational view thereof;

FIG. 3 is another side elevational view thereof taken at 90° to the view shown in FIG. 2;

FIG. 4 is a plan view thereof;

FIG. 5 is a bottom view thereof;

FIG. 6 is a top quarter perspective view of a modified form thereof;

FIG. 7 is a side elevational view thereof;

FIG. 8 is a side elevational view thereof taken at 90° from the view shown in FIG. 7;

FIG. 9 is a plan view thereof; and

FIG. 10 is a bottom view thereof.

I claim:

The ornamental design for a flange for universal joint, as shown and described.
